FLEXIBLE KNIFE MOUNTING FOR
BEAN SNIPPERSCharles E. Kerr, Hoopeston, Ill., assignor to Food
Machinery Corporation, San Jose, Calif., a cor-
poration of Delaware

Application May 14, 1943, Serial No. 486,997

1 Claim. (Cl. 146—86)

This invention relates to bean snipping machines, that is, machines used in canneries for snipping the ends off of string beans in preparing these for canning.

A type of bean snipping machine in common use includes a drum with a cylindrical shell, in which are provided a large number of closely-spaced perforations, and against the outer surface of which one or more knives are pressed. When the beans are placed in the drum and the latter rotated, ends of the beans project through the holes in the shell and are snipped off by the knives.

The drum shell in this common type of bean snipper is considerably weakened by the closely-spaced perforations therein, and owing to a number of causes in the manufacture and operation of the machine, this shell loses its true cylindrical character. The longitudinal contour of the drum at various points about its circumference thus becomes wavy and it then becomes difficult to maintain the snipping knives properly in contact with the drum.

It is an object of the present invention to provide a snipping machine in which the snipping knives conform to the surface of the drum shell in spite of longitudinal deviations from a true cylinder in the outer surface of the latter.

While heretofore snippers have been provided with flexible knives, it has been the practice where deviations as aforementioned occurred in the contour of the drum shell, to shift the entire mounting of the knife towards the shell so as to greatly increase the tension between the knife and the shell and thus cause the knife to substantially conform to the deviations in the shell. This practice, however, has resulted in excessive wear of the knife and the shell and substantially decreased the operative life of the machine.

It is another object of my invention, therefore, to provide a bean snipping machine in which the knives conform to the irregularities in the longitudinal contour of the drum shell without causing excessive wear of the knives or the drum.

The manner of accomplishing the foregoing objects, as well as further objects and advantages, will be made manifest in the following description taken in connection with the accompanying drawings in which:

Fig. 1 is a perspective view of a bean snipping machine in which is incorporated a preferred embodiment of my invention.

Fig. 2 is a fragmentary enlarged plan view of one of the knife devices of the bean snipping machine shown in Fig. 1.

Fig. 3 is an enlarged cross sectional view taken on the line 3—3 of Fig. 2.

Fig. 4 is a fragmentary view at a decreased scale taken on the line 4—4 of Fig. 3 and illustrating how the invention operates in maintain-

ing a cutting edge of a knife in conformity with the irregular surface of the drum shell of the machine.

Referring specifically to the drawings, the preferred embodiment of the invention illustrated therein is incorporated in a bean snipper 10 having a frame 11 having bearings 12 in which are mounted trunnions 13 of a tiltable gimbal 14 having bearings 15 at its ends which rotatably support a drum 16 having a shell 17. The bearings 15 are provided with suitable openings one of which is fitted with a hopper 20 through which string beans may be admitted into the drum 16. The drum 16 is tiltable by rocking the gimbal 14, so as to discharge a snipped batch of beans from the drum 16 into a hopper 25 having a bean elevator 26 which delivers the beans to a conveyor and sorting table 27.

The shell 17 is made of relatively light material having formed therein a multiplicity of small frusto-conical perforations 28 through which the ends of beans contained in the drum 16 are adapted to extend. In order to give the maximum room in this drum for beans, the shell 17 is preferably unsupported between its opposite ends. These characteristics of the shell 17 make it subject to aberrations from a true cylindrical surface.

For one thing, it is the practice, when manufacturing the shell 17, to grind the exterior surface of this with a grinding tool which is fed across the surface of the shell as the latter rotates on its axis. The grinding tool must be placed against the shell and the pressure thus exerted is often sufficient to flex the shell so that the tool does not cut as much from the shell as it is supposed to and when the tool has passed a certain area of the shell which has thus yielded that area springs back to a radius which is greater than that to which the rest of the drum is being ground down. Then the drum is subject to damage during use and to warping when heated for the purpose of making repairs. These and other causes combine to destroy the true cylindrical character of the shell 17.

Provided on the frame 11 is an electric motor 30 which is connected in a manner well known in the art to the drum 16 through a suitable transmission (not shown) for rotating this drum in the bearings 15.

The snipper 10 is provided with a pair of knife devices 35 and 36. These devices are identical, the only difference being that the device 35 is mounted on base members 40 secured by bolts 41 to the gimbal frame 14 whereas the knife device 36 is mounted in a similar manner on base members 42 provided on the drum bearings 15. A description of the knife device 35 will therefore suffice for both of these devices.

The device 35 has a main angle iron 45 pro-

vided with blocks 46 at its opposite ends, these blocks having slots 47 through which cap screws 48 extend to be screwed into suitable threaded holes provided in brackets 50 which are pivoted at their outer ends on base members 40 the latter having set screws 51 by which the inner ends of the brackets 50 may be raised or lowered. Surrounding the cap screws in the slots 47 are sleeves 52 which are of sufficient length to prevent the bolt 48 binding on the block 46 and to leave the latter free to shift within the limits provided by the slots 47.

Formed on each bracket 50 is a stud 53 having a horizontal bore 54 through which a threaded bolt 55 slidably extends, this bolt being tapped into a suitable hole provided in the adjacent block 46 (see Fig. 3). By the manipulation of adjustment and lock nuts 56 and 57 on the bolts 55, opposite ends of the angle iron 45 may be shifted inwardly or outwardly from the shell 17. After any such adjustment the nuts 56 and 57 may be set so as to hold the angle iron 45 in its new adjusted position.

The upper flange 60 of the angle iron 45 is preferably reinforced by a bar 61 welded thereto and the upper or mounting edge 62 of a knife 63 is clamped between this bar and a reinforcing strap 64 by a series of spaced bolts 65.

The knife 63 is preferably a highly flexible blade of high grade steel or bronze or the equivalent and is quite thin so that its lower portion is relatively easily flexed. A cutting edge 66 is formed along the lower edge of the knife 63, it being preferable that this edge be held at all times in contact throughout its length with the outer surface of the cylindrical shell 17.

To accomplish this, the knife 63 has a series of holes 70 provided therein, these being spaced throughout the length of the knife. Received in these holes and threaded through corresponding aligned holes 71 in the angle iron flange 60 are bolts 75 having nuts 76 for locking these bolts in suitable adjusted positions in the holes 71. As will be observed, the heads of the bolts 75 are relatively flat and lie between the knife 63 and the shell 17. Coiled about each of the bolts 75 between the knife 63 and the angle iron flange 60 is a compression spring 80.

The knife devices 35 and 36 are yieldably held in operative position as above described by leaf detent springs 90 which may be manually released when it is desired to swing the knife devices outwardly about their pivotal connection with the base members on which they are mounted, as for cleaning and adjusting the knives thereof.

Although no part of this invention, the snipping machine 10 is provided with a guard plate 95 which is preferably supported upon the base members 42 (see Fig. 1), the function of this being to shift back into the drum 16 those beans which extend too far through the holes 28 so that the bean ends uniformly extend only a desired distance through the holes 28 in the shell 17 when these bean ends come in contact with the knives 63.

Operation

To operate the snipping machine 10, the drum 16 is rotated by the motor 30 and while it is rotating is charged with string beans fed thereto through the hopper 20. As the shell 17 rotates with the drum 16 the beans fall downwardly therein. As the angle of the upper surface of the

beans in the drum continually increases beyond the angle of repose, the surface beans tumble downwardly into contact with the shell 17 and the ends of certain of these extend through the holes 28 in the shell 17. As these bean ends come around opposite the knife devices 36 and 35, the knives 63 thereof engage and snip off the bean ends as clearly illustrated in Fig. 3.

Wherever the knives 63 are not maintained in smooth contact with the outer surface of the shell 17, the snipping of the bean ends extending through this portion of the shell either does not take place at all or a clean cut is not made. The difficulty of maintaining this contact between the knives 63 and the shell surface is illustrated in Fig. 4 where characteristic variations in radius in the shell surface are illustrated. This view also shows that these variations occur along longitudinal elements of the shell.

In my invention this problem is solved by the action of the series of spaced individual compression springs 80 holding the knives 63 throughout their length in close snipping contact with the shell 17, in spite of the constant fluctuations in radius of those portions of the shell presented to the knives.

Owing to the provision in my invention of a plurality of separate means applied to the blade to obtain this result, it is not necessary to depend upon the resilience of the blade itself in the knife 63 for producing conformity between this knife and the contour of the cylinder. In fact, it is preferable that the blades of these knives be very supple and responsive to the individual springs 80 so that these springs can press the cutting edges 66 of the knives 63 into close conformity with the corresponding adjacent sections of the outer surface of the shell 17 while exerting only a relatively light pressure against the knife. The desired conformity between the knives and the shell is thus attained without subjecting either to undue wear.

While I have shown only a single embodiment of my invention, it is to be understood that various modifications may be made therein without departing from the spirit of the invention or the scope of the appended claim.

I claim:

50 A bean snipping machine comprising: a frame; a rotary shell provided with openings through which the ends of string beans contained within said shell may extend; means for rotatably mounting said shell on said frame; a flexible knife substantially parallel with said shell and having a cutting edge and a mounting edge; means for supporting said knife by its mounting edge on said frame with its cutting edge positioned to snip off extending bean ends as said shell rotates, said knife having a plurality of openings therein spaced longitudinally thereof intermediate its mounting and cutting edges; a series of bolts provided on said frame and extending through said openings with the heads of said bolts disposed between said knife and said shell; and a plurality of expansion springs coiled about said bolts between said frame and said knife, said springs separately and yieldably pressing said knife against portions of said shell respectively adjacent thereto to maintain the cutting edge of said knife in close shaving contact with the outer surface of said shell throughout the length of said knife regardless of local areas of said surface deviating irregularly from a true surface of rotation.

CHARLES E. KERR.
